BOTTLE VALVE

Christian F. Leng, New York, N. Y.

Application July 24, 1934, Serial No. 736,765

4 Claims. (Cl. 215—21)

This invention relates to bottle valves and has for an object to provide an improvement over my former Patent No. 1,200,373.

Another object of the present invention is to provide an improved bottle valve which is very simple in its construction, but which can be readily mounted on a bottle and when mounted permitting the contents to be readily poured from the bottle when the bottle is inverted or partly inverted.

An additional object, more specifically, is to provide a bottle valve having a shell connected with the neck of the bottle and having a valve member coacting therewith to effectively seal the neck of the bottle except when the contents are being poured therefrom with the bottle inverted or partly inverted.

A still further object of the invention is to provide a bottle valve which may be readily applied to a bottle, and which is so formed as to interlock with the neck of the bottle so that it cannot be removed without breaking some part of the bottle or the valve.

In the accompanying drawing—

Figure 1 is a longitudinal vertical section through the upper part of a bottle with a bottle valve disclosing an embodiment of the invention applied thereto;

Figure 2 is a sectional view similar to the upper part of Figure 1, but showing the bottle and associated parts partly inverted, whereby the contents of the bottle may readily flow therefrom;

Figure 3 is a transverse sectional view through Figure 1 on the line 3—3;

Figure 4 is a transverse sectional view through Figure 1 on the line 4—4;

Figure 5 is a transverse sectional view through Figure 1 on the line 5—5;

Figure 6 is a perspective view of the valve member shown in Figure 1.

Referring to the accompanying drawing by numerals, 1 indicates a bottle of any desired kind, having a neck 2 provided with a threaded portion 3, said threaded portion merging at the lower end into an annular body 4. The bottle valve includes a shell 5 having a threaded base 6 which is fitted over the threaded portion 3 and formed with the lower end turned in at 7 so as to be clinched against the body 4. In applying the shell 5, the base 6 in the interior is preferably provided with a coating of cement and the exterior of the threaded portion 3 is also supplied with a coating of cement, and while the cement is still moist the base is screwed into place and the lower end bent in at 7 so that the base is clinched in place and

also held by the threads. This will prevent anyone from removing the shell 5 without breaking the same or the bottle. As an additional retaining structure, the neck 2 is provided with any desired number of sockets 8 and part of the base 6 is forced into these sockets, as indicated by the depressed portions 9 in Fig. 5.

The body of the shell 5 above the base 6 is substantially tubular, as shown in Fig. 3, but is provided with a number of small guide ribs 10, and a pair of inwardly extending guides 11. The shell and associated parts have been shown as being formed of metal, but it is to be understood that these parts may not only be formed of metal but of other desired material without departing from the spirit of the invention.

When formed of metal the ribs 10 are pressed inwardly and also the guides 11 are pressed inwardly to a greater extent than the ribs 10, as clearly shown in Fig. 3. A valve member 12 is fitted into the body of the shell and provided with a large tubular portion 13, and a small tubular guiding portion or stem 14 which is closed at the bottom. The portion joining the parts 13 and 14 is rounded as indicated at 15. This rounded part 25 rests against the valve seat 16 formed on the valve plate 17, which plate is clamped against the guide plate 18 by the shoulder 19. The guide plate 18 is provided with a number of guiding projections or fingers 20 which loosely engage the stem 14 and guide the same as the valve moves towards and from its seat 16. The large tubular portion 13 of the valve 12 is provided with pressed in portions presenting grooves 21 which accommodate the guides 11, as shown in Fig. 3, the engagement being rather loose so that the valve member 12 may freely move back and forth. While the valve member 12 may freely move back and forth there is very little movement to permit any turning or rocking thereof, but if there should be any rocking the curvature of the section 15 of seat 16 will take care of this action.

It will be understood that when the parts are in closed position they will appear substantially as shown in Fig. 1, but when inverted or partly inverted the valve member 12 will move downwardly to the position shown in Fig. 2 and against the baffle 22, thus providing ample passageway for the liquid in the bottle, which liquid may move as indicated by the arrows in Fig. 2.

It will be noted that the upper end of shell 5 is provided with a restricted portion or spout 23 in which a cork 24 is removably mounted. This cork must be removed before the bottle is inverted as otherwise the liquid could not escape.

The baffle 22 is made solid and with a number of slots or notches 25 extending from the periphery inwardly. This baffle is preferably of metal and somewhat resilient so that when the parts are assembled it may be forced upwardly through the base and thence past the various ribs, and finally snapped into the annular groove 26 where it remains and prevents anyone from forcing a wire or other instrument to dislodge the valve member 12.

10 I claim:—

15 1. A valve mechanism for bottles, comprising a casing provided at its upper end with an outlet, and with inwardly extending vertically disposed 20 guide ribs, means at the lower ends of said guide ribs forming a valve seat, a valve member having a tubular extension closed at one end, a plurality of guide fingers for guiding said extension so that it will move substantially in a straight line toward 25 and from the bottom of the bottle as the valve member is guided by said ribs, and a baffle carried by said casing spaced above said valve member, said baffle being provided with openings at the periphery.

30 2. A valve mechanism for bottles, comprising a casing formed with a plurality of inwardly extending guide ribs, and a pair of inwardly extending guides extending inwardly further than the ribs, a valve member having a closed end and inwardly pressed grooves for receiving said guides, whereby the valve member is permitted a back and forth movement, a valve seat positioned to be engaged at said valve member, and a baffle carried by said casing above the valve member, said

baffle being formed solid in the center and notched at the periphery, said casing being provided with a pouring spout arranged above said baffle when the device is in a vertical position.

3. A valve mechanism for bottles for permitting the pouring of liquid therefrom but preventing the insertion of liquid, including a casing rigidly secured to a bottle, a valve seat arranged on top of said bottle, a cylindrical shaped valve member having a tapering bottom merging into a tubular extension, said valve member being positioned so that the tapering portion will normally rest on said seat, means arranged beneath the seat presenting fingers for guiding said extension so that it may freely reciprocate but is prevented from any appreciable other movement, means above the valve seat forming part of the casing for guiding the upper part of the valve member and presenting passageways between the casing and the valve member, said casing having an outlet opening and a partly foraminous baffle arranged between said opening and said valve member.

4. A valve mechanism for bottles, comprising a casing rigidly secured to a bottle and provided with a plurality of inwardly extending guides, a valve seat, a valve member normally resting on said seat, said valve member being tubular and having a pair of pressed in portions presenting grooves in which said guides function, said casing having an outlet opening and a baffle arranged between said valve member and said outlet opening.
